UNITED STATES PATENT OFFICE

CAMPBELL M. HUNTER, OF LONDON, ENGLAND

BURNER

Application filed May 24, 1927. Serial No. 193,889.

My invention relates to atmospheric gas and oil burners of relatively large capacity designed primarily for use for industrial purposes.

5 The principal object of my invention is to provide means for burning a combustible mixture composed either of oil, steam and air, or gas, steam and air, or oil, gas, steam and air so as to meet any particular requirement or condition. Another object of my 10 invention is to mount the oil jet in a manner permitting its ready removal for purposes of cleaning and replacement. Another object of the invention is to provide simple 15 and efficient means whereby either air or gas, or both, may be ejected into the mixing chamber of the burner by a fluid under pressure.

A primary feature of the invention consists 20 of a burner having a mixing chamber, a plurality of adjacent compartments, one of the compartments having communication with an oil supply and the other having communication with a fluid supply under 25 pressure, each of the compartments having a jet for conveying their respective fluids to the mixing chamber, and the oil jet being removably mounted.

Another feature of the invention consists 30 of a burner having a mixing chamber and gas and air ports, the axes of said ports being spaced from and extending at an angle to the longitudinal axis of the mixing chamber, and a common discharge opening 35 leading into said mixing chamber from the said ports.

In the drawings illustrating a preferred embodiment of my invention,—

Figure 1 is a plan view of the burner and 40 a suitable arrangement of the pipe connections and valves.

Figure 2 is a plan view of the burner, partly in elevation and partly in section.

Figure 3 is a sectional view taken on the 45 line 3—3, Fig. 2.

Figure 4 is a rear end elevational view of the burner.

Figure 5 is a sectional view taken on the 50 line 5—5, Fig. 3.

In the drawings the burner is shown as

formed with a chamber 2 into which the various fluids comprising the combustible mixture are adapted to flow and wherein they are intimately and effectively mixed before being discharged therefrom. For inducing increased velocity of flow of the mixture from the chamber the latter is formed with a constricted exit throat 3 merging into a somewhat larger discharge nozzle 4.

Above the mixing chamber and on opposite sides thereof, the burner has a gas port 5 and an air port 6. These ports may advantageously be tangentially arranged with respect to the mixing chamber, and their axes are preferably coincident with each other and substantially normal to the longitudinal axis of the burner. Adjustably mounted in the port 6 for controlling the admission of air is a screw threaded valve member 7 having apertures 8 the effective size of which may be varied by rotating it in the desired direction. Secured to a portion of the valve 7, preferably by means of a rivet 9, is a spring finger 10 which may, if desired, be employed for frictionally engaging with the wall of the port for maintaining the valve in a given position of adjustment.

The gas port 5 connects with a gas supply pipe 11 having a valve 12 for regulating the quantity of gas to be delivered to the burner. This port has communication with the air port 6, and they both have communication with an opening 13 formed in the top wall of the mixing chamber so that the gas and air may enter the mixing chamber at a common point. To the rear of the mixing chamber 2 and preferably in axial alignment therewith is a detachably connected heating chamber 14. A diagonally extending partition wall 15 divides this latter chamber into longitudinally disposed compartments 16 and 17. These compartments are provided with ports or openings

18 and 19 which are preferably diametrically opposed for receiving respectively oil and steam from the supply pipes 20 and 21, each of the pipes being provided with control valves 22. The provision of the valve 22 in

the pipe 20 for regulating the supply of oil delivered to the burner, eliminates the use of the needle valve usually employed for that purpose.

5 The wall of the steam compartment 17 adjacent the mixing chamber 2 projects forwardly into the latter and is provided with an opening 23 constituting a steam jet. The opening is preferably lined with a rustless 10 annulus 24 cast in place, such annulus being advantageously made of monel metal.

Concentrically spaced within the steam jet 23 and coextensive therewith is the oil jet 25 having communication with the oil compartment 16 by the radial openings 26. The oil jet extends through an aperture 27 in the partition wall 15 and is detachably mounted in the rear wall of the heating chamber in the opening 28. By this means 20 the oil jet may be readily removed without disassembling the burner for the purpose of cleaning the steam and oil jets or for replacement of the latter. The opening 28 is effectively sealed by a detachable screw 25 threaded plug 29.

To create a reduced pressure at the discharge end of the oil jet in order to cause the oil to flow into the mixing chamber by induction, the annular space between the jets 30 increases in cross sectional area in the direction of flow of the steam. This is preferably accomplished by tapering the outer periphery 30 of the discharge end of the oil jet. By this means and by locating the ends 35 of the jets rearwardly of the center of the opening 13 in the mixing chamber, gas and air are efficiently ejected or induced into the said chamber. Since the jets are arranged substantially coaxial with the mixing chamber a thorough atomization of the oil and 40 subsequent mixing with the other ingredients of the combustible mixture is obtained.

By the combination of these various features the burner has been found under actual 45 test to have a burning capacity ranging from two to thirty-three barrels of oil for twenty-four hours, the quantity of oil consumed being primarily dependent upon the pressure at which the oil ejecting fluid is maintained.

50 In order to obviate any danger from backfiring a gauze damper 31 may be inserted in the gas inlet pipe in any suitable manner.

It will be appreciated that, due to the relative locations of the steam and oil compartments, the oil is effectively heated before being introduced into the mixing chamber.

While under most conditions steam will prove to be the most efficient agent for atomizing the oil and inducing it and the gases into the mixing chamber, it is obvious that compressed air may suffice to accomplish these results.

From the foregoing description it will be readily perceived that by proper manipula-

tions of the valves 7, 12 and 22, not only can the quantity of the various fluids be efficiently regulated, but the constituent parts of the combustible mixture may be varied. For example, by closing the valve 12 and opening the other valves a mixture of oil, steam and air is obtained; by opening valve 12 and closing the oil valve, a mixture of gas, steam and air is obtained, and by opening all of the valves a mixture of oil, gas, steam and air may be used.

I claim:

1. A burner comprising a mixing chamber, a gas port and an air port, the axes of said ports being in alinement and spaced from and extending at an angle to the longitudinal axis of the chamber and the said ports having communication with the mixing chamber through a common discharge opening leading into the side of said chamber.

2. A burner comprising a mixing chamber, gas and air passageways having a common discharge opening into said chamber, and oil and steam passageways terminating in said chamber to the rear of a line intersecting the longitudinal axis of the mixing chamber and passing through the center of the gas and air discharge opening.

3. A burner of the fluid fuel type having a mixing chamber, a second chamber having a partition dividing it into a plurality of compartments, one of said compartments having communication with an oil supply and the other having communication with a supply of heated fluid, and a jet for each of said compartments for conveying their respective fluids to the mixing chamber, the jet for the oil compartment being removably mounted and having a radial opening communicating with said oil compartment and extending through said plurality of compartments.

4. A burner of the fluid fuel type having a mixing chamber, a second chamber having a partition dividing it into a plurality of adjacent compartments, one of said compartments having communication with an oil supply and the other having communication with a fluid supply under pressure, each of said compartments having a jet for conveying their respective fluids to the mixing chamber, and means permitting the removal of the oil jet from the oil compartment said oil jet having a radial opening communicating with said oil compartment.

5. A burner of the fluid fuel type having a mixing chamber, a second chamber having a partition dividing it into a plurality of adjacent compartments, one of said compartments having communication with an oil supply and the other having communication with a fluid supply under pressure, and a jet for each compartment adapted to convey the fluid contained therein to the

mixing chamber, the oil jet extending within and being arranged concentrically with respect to the other jet and being provided with substantially radial openings communicating with the oil compartment.

5 6. A burner of the fluid fuel type having a mixing chamber, a chamber having a partition dividing it into a plurality of compartments, one of said compartments having communication with an oil supply and the other having communication with a steam supply, an oil jet and a steam jet each being adapted to respectively convey the oil and steam to the mixing chamber, 10 the rear wall of said oil compartment being apertured to receive and removably support the oil jet, and a plug for closing said aperture.

15 7. A burner of the fluid fuel type having a mixing chamber, a second chamber having a partition dividing it into a plurality of adjacent compartments spaced longitudinally of the burner, one of said compartments having communication with an oil supply and the other having communication with a fluid supply under pressure, a jet for conveying the oil from its compartment and discharging it into the mixing chamber, said jet comprising a hollow member having radially disposed openings communicating with the oil compartment, and means for closing said jet rearwardly of said openings.

20 8. A burner of the fluid fuel type provided with a mixing chamber, coaxial gas and air passageways, an opening in a wall of the mixing chamber having communication with both of said passageways, and means for injecting fluid under pressure 25 into said mixing chamber to the rear of the line passing through the center of the opening and normal to the longitudinal axis of the mixing chamber.

30 9. A burner of the fluid fuel type having a mixing chamber provided with an opening for the admission of air, a plurality of adjacent compartments, one of said compartments having communication with an oil supply and the other having communication with a fluid supply under pressure, and a jet for each of the compartments adapted to convey their respective fluids to the mixing chamber, the said jets being arranged in spaced relation one within the 35 other and having their delivery ends terminating substantially at said opening, the space between the jets increasing in cross sectional area in the direction of flow of the fluids.

35 10. A burner having a mixing chamber and provided with a plurality of oppositely disposed ports, one of said ports being an air port and one of said ports being a fuel port, a common discharge opening connecting 40 said ports with said chamber, the axis

of said discharge opening extending at an angle to the axis of said chamber, and oil and steam passageways terminating in said chamber in line with said opening.

45 11. A burner comprising a mixing chamber having an air opening in a side wall thereof, and oil and steam jets terminating within said chamber, the said jets terminating at their delivery ends in line with said opening and being concentrically arranged one within the other and being coaxial with respect to the mixing chamber and the space between them adjacent their delivery ends increasing in cross-sectional area in the direction of flow of the fluids.

50 In testimony whereof I affix my signature.

CAMPBELL M. HUNTER.
